UNITED STATES PATENT OFFICE.

GEORGE A. WOODMAN, OF CHICAGO, ILLINOIS.

HOUSE-CAR END CONSTRUCTION.

1,317,121.

Specification of Letters Patent. Patented Sept. 23, 1919.

Application filed February 27, 1918. Serial No. 219,366.

To all whom it may concern:

Be it known that I, GEORGE A. WOODMAN, a citizen of the United States, residing at Chicago, in the county of Cook and State of Illinois, have invented certain new and useful Improvements in House-Car End Constructions, of which the following is a specification.

This invention relates to house-car end construction and has for its primary object the provision of means for strengthening car ends and rendering them more resistant to the severe shocks to which they are subjected in use.

15 A further object of my invention resides in the provision of a one piece strengthening member of rolled section adapted to be secured to the car ends to stiffen the latter.

Further objects and advantages of my invention will be apparent as it is better understood by reference to the following specification when read in connection with the accompanying drawing, illustrating the preferred embodiments thereof, in which:

25 Figure 1 is an end elevation, partially in section of a car embodying my invention;

Fig. 2 is longitudinal section on the line 2—2 of Fig. 1;

30 Fig. 3 is a horizontal section on the line 3—3 of Fig. 1;

Fig. 4 is a detail in perspective of the one piece member of rolled section, and

Fig. 5 is a detail in perspective illustrating a slightly different form of my invention.

Referring to the drawing, 5 and 6 indicate respectively the end and side sills of a car upon which the floor 7 is supported. The end and side plates 8 and 9 respectively are supported in spaced relation to the sills 5 and 6 by the upright members 10 and braces 11 which in turn support the outside sheathing 12 and lining 13. The roof 14 is supported by the carlines 15 mounted on the side plates 9 and a running board 16 is supported above the roof 14 on the brackets 17, bolted to the end plates 8. The foregoing is the usual house car construction and forms no part of my invention. The 50 ends of housecars are subject to severe shocks in use owing to the movement of material contained therein when force is suddenly applied to move the car. This results in frequent breaking down of the ends so that expensive repairs are necessary from time to time. My invention is designed to

provide inexpensive means for strengthening the ends so that they will successfully withstand shocks. Thus the life of the car will be materially lengthened and the cost of 60 upkeep reduced.

In carrying out my invention I provide a one piece end member 18 of rolled section and formed substantially in the shape of an inverted U, as clearly indicated in Fig. 65 4 of the drawing. This member is secured in position on an end of the car by bolts 19 extending through the inner flange of the member and engaging the end sill and plate as well as the outside sheathing and lining of 70 the car end. This forms a particularly rigid and shock resistant combination as all shocks affecting the end of the car are immediately transmitted and distributed to the member 18 which is sufficiently strong to 75 eliminate the possibility of breakage.

Preferably top braces 20 are secured by the bolts 19 extending through the flange of the member 18 at the top thereof and through the end plate 8. The free ends of 80 these braces are secured by bolts 21 extending through the side plates 9. Any tendency, therefore, of the upper end of the member 18 to move outwardly is resisted by the top brace attached thereto and transmitting the stress to the side plates. 85

I also preferably provide a member 22 of rolled section which is secured at its ends by bolts 23 to the outer sheathing and lining of the car end and extends transversely 90 across the car end through suitable slots 24 provided near the lower ends of the member 18. Obviously as illustrated in Fig. 5, 3 separate members 24' may be bolted to the car ends and connected to the ends of the 95 member 18 by angle plates 25, held in position by the bolts 26. The slots 24 are thus eliminated and the full strength of the rolled section preserved.

From the foregoing it will be readily understood that I have perfected a house-car end-structure having certain novel features which materially strengthen it without adding greatly to the weight or cost of the structure. The rolled section of which the 105 member 18 is composed is extremely light in proportion to its strength and by forming it in a single piece I preserve its maximum shock resistant efficiency.

It will be apparent, therefore, that various changes may be made in the form, arrangement and construction of the parts,

without departing from the spirit and scope of the invention, or sacrificing any of its material advantages, the form hereinbefore described being merely the preferred embodiment thereof.

I claim:

1. A house-car end-construction embodying a bent one piece member of rolled section having spaced and connected legs section having spaced and connected legs secured to the end sill and plate of the car, the longer sectional axis of said member being perpendicular to the car end.
2. A house-car end-construction embodying a one piece bent U-shaped member of rolled section, the legs of said member being secured to the end sill and plate of the car, and said member being arranged with its longer sectional axis perpendicular to the car end.
3. A house-car end-construction embodying a bent one piece member of rolled section having spaced and connected legs, said

member being secured to the car exteriorly thereof with its longer sectional axis perpendicular to the car end.

25

4. A house-car end-construction embodying a bent one piece steel member of rolled section having spaced and connected legs vertically disposed at the end of the car and secured to the end sill and plate thereof, said member being arranged with its longer sectional axis perpendicular to the car end.

30

5. A house car end construction embodying an end sill and plate and an inverted U-shaped member of rolled section bolted to the car end exteriorly of the car and connecting said sill and plate, the longer sectional axis of said member being in perpendicular relation to the car end.

35

GEORGE A. WOODMAN.
